(57) **CLAIM**

The ornamental design for a vehicle fender flare, as shown and described.

DESCRIPTION

FIG. 1 is a perspective view of a vehicle fender flare for the right side of a vehicle showing our new design.

FIG. 2 is a front elevational view thereof.

FIG. 3 is a top plan view thereof.

FIG. 4 is a bottom plan view thereof.

FIG. 5 is a rear elevational view thereof.

FIG. 6 is a right side elevational view thereof; and,

FIG. 7 is a left side elevational view thereof.

The vehicle fender flare for the left side of the vehicle is a mirror image thereof, but is not shown in the claimed design. The broken lines illustrate portions of the vehicle fender flare that form no part of the claimed design.
